(57) CLAIM

The ornamental design for a surfboard carrier, as shown and described.

DESCRIPTION

FIG. 1 is a rear and side perspective view of the surfboard carrier showing my new design in use; wherein the broken lines indicating a handle, a surfboard and a person carrying the surfboard are illustrative of the environment only and form no part of the claimed design.

FIG. 2 is a front and side perspective view of the surfboard carrier; wherein the broken lines indicating a handle are illustrative of the environment only and form no part of the claimed design.

FIG. 3 is a top plan view thereof; wherein the broken lines indicating a handle are illustrative of the environment only and form no part of the claimed design.

FIG. 4 is a front elevation view thereof; wherein the broken lines indicating a handle are illustrative of the environment only and form no part of the claimed design; and,

FIG. 5 is a side elevation view thereof; wherein the broken lines indicating a handle are illustrative of the environment only and form no part of the claimed design.
